UNITED STATES PATENT OFFICE.

ARTHUR W. TATHAM, OF DETROIT, MICHIGAN.

ART OF MAKING WAX PATTERNS FOR CASTINGS FOR DENTAL WORK.

1,033,489.

Specification of Letters Patent.

Patented July 23, 1912.

Application filed April 15, 1911. Serial No. 621,196.

To all whom it may concern:

Be it known that I, ARTHUR W. TATHAM, a citizen of the United States, residing at Detroit, county of Wayne, State of Michigan, have invented a certain new and useful Improvement in the Art of Making Wax Patterns for Castings for Dental Work, and declare the following to be a full, clear, and exact description of the same, such as will enable others skilled in the art to which it pertains to make and use the same, reference being had to the accompanying drawings, which form a part of this specification.

This invention relates to the art of making wax patterns for castings for dental work.

It has for its object an improved process of constructing the small wax patterns or images used by dentists in making castings, generally castings of gold, for many purposes connected with the dental art.

For purposes of illustration, I have selected as samples of the work to be done in carrying out this process, the two forms shown in the accompanying drawings, in which:—

Figure 1, shows a defective tooth prepared for repair by fixing thereto a "filling". Fig. 2, shows a piece of wire gauze used in the process. Fig. 3, shows a section of the same piece of wire gauze as it is shaped in carrying out the process. Fig. 4, shows a section of the same piece of wire gauze as it is finally shaped and coated with wax. Fig. 5, shows a natural base or root to which is attached an artificial crown by means of a double socket made of cast metal. Fig. 6, shows the double socket used in Fig. 5. Fig. 7, is a cross section showing a root member, an artificial crown member, and the double socket by which the two are united.

To illustrate the process and the character of the pattern that is produced by carrying out the process, suppose a tooth 1 is to be provided with a filling that partially covers the crown; in producing such a filling there is employed a piece of wire gauze 2 which is used as a reinforcing member in the pattern.

4. To illustrate a different operation suppose a natural root 7 of a tooth is to have joined to it an artificial crown 8 by a metal connecting member in which there are opposed sockets contained within the rings 9 and 10 and joined by a metal connection 11; in the final casting, the metal connection or 55 tie member is a solid piece of metal with opposing cavities or sockets one of which en-

gages over the root 7 and the other of which engages under the crown 8 and which is cemented to both the root and the crown. These two illustrative structures show only 60 a few of the many structures for which the complete pattern produced by the process about to be described may be used, but these are sufficient, it is thought, to fully explain the process and make evident the range of 65 use of the process.

In carrying out the process the tooth to be treated is cleaned, decayed parts cut away, and such provision as is best adapted for the special case is made that the tooth, or portion of the tooth shall be intimately connected to and shall securely hold the casting that is to be made and placed upon it, or within the cavity in it. After the preparatory work is done a small piece of thin 75 metal preferably wire gauze of very fine mesh is laid over that part of the tooth to which the casting is to conform. The metal or mesh is crowded and pressed into close engagement with the surface of the tooth, 80 burnished along the edges of the metal, turning the metal over the edge and cavity, or the edges of the tooth as the case may be, and fitting it as closely thereto as it can be conveniently. After this fitting a coating of 85 wax is placed over the partly formed mesh and the wax coated mesh is removed from the tooth; a coating of wax is placed on the under side of it and the form is again crowded to its place on the tooth or in the 90 cavity crowding out superfluous wax from underneath it and crowding the wax more intimately into the sinuosities of the cavity. The now partially completed pattern is removed from the tooth, the edges of the wire 95 gauze clipped off with scissors until the projecting edges are trimmed away. The partly finished pattern is replaced in the cavity or on the tooth and the wax is pressed and worked entirely over the edges of the 100 metal using a burnishing tool or some similar implement and warming the tool if necessary.

The extreme edge of the pattern is made very thin, sometimes so thin that it scarcely 105 equals the five one-thousandths of an inch (the wire gauze used may be as thin as four one-thousandths of an inch in thickness). When the pattern has been fully shaped it is again removed from the tooth and covered 110 with investing material in the ordinary way of making a mold. The further treatment

is quite similar to the treatment of the ordinary wax patterns used in the art; after the pattern has been placed in the flask and the arrangements for the sprue perfected the 5 wax is removed by melting it out from the mold leaving the metal gauze suspended in the mold. The molten gold is then poured into the mold and the metal gauze becomes a part of the final casting, it disappears as 10 a mesh, but remains as a metal.

In carrying out this process, the pattern may be removed and replaced as often as may be necessary. It can be very easily removed because the adhesion of the wax to 15 the included strengthening metal so much exceeds the adhesion of the wax to the tooth being treated, that the pattern may be removed without distorting even the thinnest edges of the parts, and when removed may 20 be handled readily without danger of injuring even the thinnest edges, and the facility of removing and replacing enables it to be shaped and formed on both its attaching side and its free side exactly as 25 may be desired or required. For example, if it be desired to close the teeth upon the partially finished pattern in order to shape the pattern to correspond with the opposing tooth in the jaw, or if it be desired to 30 close the teeth on a crown, such as is shown in Fig. 5, in order to get the proper shape and proper length of the projection of the crown; this may be done without fear of injury to the pattern itself.

35 The process can be used for the production of a tie member to hold an artificial crown to a natural root, such as is shown in Fig. 6, by making a reinforced form in connection with the root member and another reinforced form in connection with the crown member, which two reinforced forms are held together by an intermediate 40 layer of wax, the complete pattern consists in this instance, of two reinforcing members embedded in a unitary mass of wax, and one part of the pattern is adapted to engage over the root, and another part of the pattern is adapted to engage the artificial crown; these are formed with great 45 accuracy to engage closely and entirely around the root and crown; the pattern is very thin at its edges and does not present a thick band around either part and yet it has great firmness and preserves its shape 50 and integrity during the period of manipulation and the gauze is held in the mold accurately after the wax is melted out. The casting made from this pattern comprises a cup part 9 and a cup part 10 joined by 55 metal connection 11 and of these the cup part 9 is adapted to engage and in the completed work does engage closely over the root 7 of the tooth and the cup shaped part 10 is adapted to engage, and the finished 60 work does engage closely and accurately 65

around the under part of the crown 8 and the two cup shaped parts are joined by the solid metal part 11.

The pin 12 is used in the ordinary way as an anchor, or it may be omitted in many 70 characters of work.

It is evident that this process may be used in all dental work where it is desirable to join a metal piece to the natural part of the tooth, whether the metal piece 75 itself be a finishing piece or a mere union piece between the root and the artificial part of the tooth that is connected to the root. It is also evident that the same process may be used to great advantage in work 80 where all the parts to be connected are artificial, and its uses in out-of-the-mouth dentistry may be just as great as its uses in in-the-mouth dentistry.

In casting the final form to correspond 85 to the pattern, the usual and well known method of packing the pattern in the mold material and the formation of sprues is followed out in the well known way of casting.

In making large gold work, the gold may 90 be cast over a cage made from the gauze in which is included a core of any suitable material used to avoid expense and weight; in such work the cage while yet unfilled may be shaped as desired and the core is 95 afterward placed in and closed entirely in.

What I claim is:—

1. The process of producing a pattern 100 for dental purposes, comprising a preparation of the part to which the pattern is to conform, placing over the part a piece of gauze, shaping the gauze to conform roughly to the part, coating the shaped gauze on both sides with wax, again shaping the waxed metal to conform to the part, trimming off superfluous gauze around the edges, and giving a final shape to the external surface of the waxed gauze, substantially as described.

2. The process of producing a pattern 110 for dental purposes, comprising the placing over the part to which the pattern is to conform a piece of gauze, shaping the gauze to conform roughly to the part, coating the shaped gauze with wax, shaping the 115 waxed gauze to conform to the part, substantially as described.

3. The process of producing a pattern for dental purposes, comprising the placing over the part to which the pattern is to conform a piece of gauze, shaping the gauze to conform roughly to the part, coating the shaped gauze with wax, shaping the waxed gauze to conform to the part, embedding the same in a porous heat-resisting mold 120 and applying heat to melt and absorb the wax, substantially as described.

4. The process of producing a pattern for dental purposes, comprising the shaping of a metal reinforcing base to corre- 130

spond with the pattern to be made, coating the metal reinforcing base with the plastic and shaping the plastic to form the finished pattern, substantially as described.

5. The process of producing a pattern for dental purposes, comprising first the rough shaping of a piece of metallic plastic foraminiferous material to the part to which the pattern is to conform, finishing the

shaping by adding thereto a non-metallic plastic material to conform to the part referred to, substantially as described.

In testimony whereof, I sign this specification in the presence of two witnesses.

ARTHUR W. TATHAM.
